Fig. 1.

UNITED STATES PATENT OFFICE

LAWRENCE F. BAASH, OF LOS ANGELES, AND WILLIAM H. MAXWELL, OF BEVERLY HILLS, CALIFORNIA

TONGS

Application filed March 31, 1930. Serial No. 440,269.

This invention relates to tools for handling pipe, etc., and relates more particularly to tongs for handling and gripping pipe and like objects.

5 It is a general object of the present invention to provide simple, practical, and effective tongs for handling pipe and the like.

It is another object of the invention to provide tongs in which the actuating line 10 or other means for turning or operating the tool may be employed to directly operate a gripping jaw into gripping engagement with a pipe or like part engaged by the tool.

It is another object of the invention to provide 15 tongs of the character mentioned in which the operating line for operating the tongs and the gripping jaw extends from the outer end of the handle of the tool so that a substantial leverage is obtained for turning the tool.

Another object of the invention is to provide 20 a tool of the character mentioned that is extremely simple of construction and embodies a minimum number of simple parts.

Another object of the invention is to provide 25 tongs that are well balanced and easy to handle and operate and in which the parts for operating the gripping jaw are encased and protected against injury.

30 It is a further object of the invention to provide tongs which embody means for automatically returning the gripping jaw to the retracted position after actuation.

Other objects and features of our invention 35 will be best and more fully understood from the following detailed description of a typical form and application of the invention, throughout which description reference is had to the accompanying drawings, in 40 which:

Fig. 1 is a side elevation of the tongs provided by our present invention illustrating the tool engaging a pipe. Fig. 2 is a top or plan view of the tongs. Fig. 3 is a horizontal 45 detailed sectional view of the tool. Fig. 4

is an enlarged horizontal detailed sectional view of the head portion of the tongs. Fig. 5 is an enlarged transverse detailed sectional view taken as indicated by line 5—5 on Fig. 3.

The broader features of our invention are 50 capable of embodiment in tools of various characters for handling various forms of objects. Throughout the following detailed disclosure we will confine the description to one simple form of the invention intended for handling comparatively large pipe, etc. It is to be understood, however, that the invention is not to be considered limited to the 55 particular embodiment of the invention herein disclosed but is to be taken as including 60 any modifications or variations that may fall within the scope of the claims.

The tool provided by this invention includes, generally, a pipe encircling head 10, a gripping jaw 11 slidably carried by the 65 head 10, a handle 12 for the head 10, means 13 for operating the gripping jaw 11 directly by an operating line L, or the like, and means 14 for returning the gripping jaw 11 and the 70 means 13 to the normal position after actuation.

The head 10 is provided to encircle or receive a part such as a pipe P and may include two principal or main parts, namely, a body 75 15 and a gate 16. In the preferred embodiment of our invention the body 15 of the head 10 carries the gripping jaw 11 and is provided with the operating lever or handle 12. The body 15 may be a single rigid part of substantially U-shaped configuration. The 80 body 15 may have two spaced side parts 17 and 18 between which there is a recess or opening 19. The opening 19 is provided to slidably carry the gripping jaw 11 and its opposite side walls 20 are made parallel and 85 flat to slidably carry the gripping jaw 11.

The gate 16 of the pipe encircling head 10 is in the nature of a closure for the opening 19. The gate 16 is provided to extend around the pipe P to retain it in position for engage- 90

ment by the gripping jaw 11. The gate 16 may be of any suitable construction and may be mounted on the body 15 in any desired manner. In the case illustrated the gate 16 is a simple rigid part pivotally mounted on the outer end of the side part 17. The gate 16 may be pivotally mounted on the side part 17 by a pivot pin or bolt 21. The inner side 22 of the gate 16 is curved to effectively engage or seat against the pipe P. Pipe engaging parts in the form of dies 23 may be arranged in recesses in the inner side 22 of the gate to engage the pipe.

Suitable latch means may be provided in connection with the gate 16 for releasably holding the gate in the closed position. In the particular form of the invention illustrated in the drawings a latch 24 is pivotally mounted at the outer or free end of the gate 16 to cooperate with a latch catch or lug 25 on the side part 18 of the body. The latch 24 may be pivotally mounted in a recess 26 at the gate 16 by a pivot pin 27. The latch 24 and the lug 25 are formed and related so that the latch automatically cooperates with the lug to releasably hold the gate in the closed position upon the gate being operated or swung to the closed position. A spring 27^a may be provided to yieldingly hold the latch 24 in a position to cooperate with the lug 25 when the gate is closed. The latch may be provided with a handle 28 which may also serve as a handle for the gate.

The pipe gripping element or jaw 11 is slidably carried in the opening 19 of the body and is operable by the operating line through the means 13 to grip the pipe P. The gripping jaw 11 may be a unitary part and may be shaped to effectively operate in the opening 19. The jaw 11 may have flat parallel sides 29 to slidably operate on the walls 20 of the opening 19. The pipe engaging end of the gripping jaw 11 is preferably made concave or curved to effectively engage the pipe. Pipe engaging dies 30 may be seated in recesses in the active end of the jaw 11 to engage or grip the pipe.

In accordance with the preferred form of our invention means is provided for resisting relative rotation between the tool and the part being handled at the start of actuation of the means 13. In the case illustrated the means for initially resisting rotation between the tool and the pipe is provided on the gripping jaw 11 and includes a stem 31 slidably carried in the jaw 11 having its outer end extending into a recess 32 in the active end of the gripping jaw and its inner end extending into a socket 33 in the rear end of the jaw 11. A block 34 is tiltably or pivotally mounted at the outer end of the stem 31 in the recess 32. The block 34 is carried so that it is free to tilt about an axis transverse of the stem 31. The block 34 carries two spaced pipe engaging members 35. The members 35 may be

provided with serrations or teeth to grip the pipe P. A spring 36 is provided in the recess 32 to normally urge the members 35 into gripping engagement with the pipe P. The spring 36 may surround the stem 31 and may be arranged between the bottom of the recess 32 and the block 34.

The handle 12 is provided to facilitate the handling and operation of the tool and carries the means 13 for operating the gripping jaw 11. The handle 12 is provided on the body 15 of the head 10 and may be formed integral with the body. The handle 12 projects outwardly or rearwardly from the body 15 and is preferably made comparatively long.

The means 13 is provided to operate the gripping jaw 11 by force applied to the operating line L for operating or turning the tool. The means 13 is carried by the handle 12 and includes a rod 40 slidably carried in a longitudinal opening 41 in the handle. The rod 40 extends completely through the opening 41 from one end to the other and has its inner end connected to the gripping jaw 11. The inner end of the rod 40 extends into the outer portion of the socket 33 and may be set or locked in the socket by a pin 42 or other suitable means. The outer end of the rod 40 projects into a transverse opening 43 in the outer portion of the handle 12. A block 44 is attached to the outer end of the rod 40. The block 44 is slidable in the opening 43 and carries a pulley 45. The pulley 45 is rotatably mounted on a shaft 46 and may be mounted within a transverse opening 47 in the block. The pulley 45 is provided to carry or pass the operating line L. The operating line L is attached or secured to the operating handle 12 at a point inward of the pulley 45. The line L may be attached to the head in any suitable manner. In the case illustrated a lug 48 is provided on one side of the handle 12 and has an opening 49 for passing the line. The line L extends outwardly from the lug 48 and extends through the opening 47 to operate over the pulley 45. The line L passes laterally from the pulley 45 and may be operated in any suitable manner for operating or turning the tool. In accordance with the preferred embodiment of the invention a guide 50 is provided on the block 44. The guide 50 projects outwardly from the outer end of the block 44 and is slidable in an opening 51 in the outer end of the handle 12.

The means 14 is provided to return the gripping jaw 11 and the means 13 to their positions after actuation. The means 14 may be in the nature of spring means. The means 14 may include a spring 53 arranged to operate between the rod 41 and the body 15. The spring 53 may be a helical spring arranged in an enlargement 54 in the inner end of the opening 41. The spring 53 may surround the rod 40. One end of the spring 53

is attached to the rod 40 and the other end of the spring is attached to the body 15. The end of the inner convolution of the spring 53 may seat in an opening in the rod 40 while the outer convolution of the spring may have its end extending into an opening in the walls of the enlargement 54. Upon operation of the rod 40 inwardly the spring 53 is elongated, and when the means 13 is released the spring acts to return the jaw 11 and the rod 40 to their normal unactuated positions.

Means may be provided on the head 10 for suspending or carrying the tool. A suitable eye bolt 60 may project upwardly from the upper side of the body 15 to receive a suspension line or the like for carrying the tongs.

It is believed that the operation of the tongs provided by our present invention will be readily apparent from the foregoing detailed description. The gripping jaw 11 may be operated into secure gripping engagement with the pipe P by operating the line L to urge the rod 40 inwardly. The line L may be employed for turning or rotating the pipe as well as for actuating the gripping jaw 11. It is to be particularly noted that the tongs provided by this invention are extremely simple of construction and embody but few parts. Further, the block 44 and the various other parts of the means 13 are encased in the handle 12 so that they are protected against injury. The means 13, being carried by the handle 12, operates to balance the pipe encircling head 10 of the tool so that the tongs are easy to handle and operate. The block 44 carrying the pulley 45 may be arranged in the outer portion of the handle 12 so that a substantial leverage is obtained by operating the line L for turning the tongs.

Having described only a typical preferred form of our invention, we do not wish to limit ourselves to the specific details set forth but wish to reserve to ourselves any changes or variations that may appear to those skilled in the art or fall within the scope of the following claims.

Having described our invention, we claim:

1. A tool of the character described including, a head, a gripping element carried by the head, and means for operating the element by an operating line, including, a rod, and a pulley on the rod to be engaged by the line.

2. A tool of the character described including, a head, a gripping element carried by the head, and means for operating said element from an operating line for the tool including, a rod connected to the element, and a pulley carried by the rod for passing the line.

3. A tool of the character described including, a head, a gripping element carried by the head, a handle extending from the head, and means for operating the element by an operating line for the tool including, a rod con-

nected to the element and slidably carried by the handle and a pulley carried by the rod for passing the line.

4. A tool of the character described including, a head, a gripping element slidably carried by the head, a handle extending from the head, and means for operating the element by an operating line including, a rod connected to the element and slidably in an opening in the handle, and a pulley at the outer end of the rod for passing the line.

5. A tool of the character described including, a head, a gripping element carried by the head, a handle on the head, and means for operating the element by an operating line including, a rod connected to the element and slidably in an opening in the handle, and a pulley rotatably carried in an opening in the rod for passing the line.

6. A tool of the character described including, a head, a gripping element carried by the head, a handle on the head, and means for operating the element by an operating line including, a rod connected to the element and slidably in an opening in the handle, a block on the rod slidable in the handle and a pulley rotatably carried by the block for passing the line.

7. Tongs including, a head, a pipe gripping element carried by the head, a handle, and means for operating the element directly by an operating line attached to the handle including, a rod attached to the element slidable in the handle, and a pulley carried by the rod in an opening in the handle for passing the line.

8. Tongs including, a head, a pipe gripping element carried by the head, a handle, and means for operating the element directly by an operating line attached to the handle including, a rod attached to the element slidable in the handle, and a pulley carried by the rod at a point outward of the point of attachment of the line with the handle for passing the line.

9. Tongs including, a head, a pipe gripping element carried by the head, a handle, and means for operating the element directly by an operating line attached to the handle including, a rod attached to the element slidable in the handle, a block on the rod slidably in an opening in the handle outward of the point of attachment of the line to the handle, and a pulley rotatably carried in the block for passing the line.

10. Tongs of the character described including, a head, a gripping element carried by the head, a handle, means for operating the element directly by a line for operating the tongs including, a rod attached to the element slidably carried by the handle, and a rotatable pulley on the rod for passing the line, and means for returning the element after actuation.

11. Tongs of the character described in-

cluding, a head, a gripping element carried by the head, a handle, means for operating the element directly by a line for operating the tongs including, a rod attached to the element slidably carried by the handle, and a rotatable pulley on the rod for passing the line, and means for returning the element after actuation, including a spring attached to the head and the element.

10 12. Tongs of the character described including, a head, a gripping element carried by the head, a handle, means for operating the element directly by a line for operating the tongs including, a rod attached to the element slidably carried by the handle, and means for initially resisting relative rotation between the head and an object.

20 13. Tongs of the character described including, a head, a gripping element carried by the head, a handle, means for operating the element directly by a line for operating the tongs including, a rod attached to the element slidably carried by the handle, and means for initially resisting relative rotation between the head and an object, including a spring pressed pipe gripping member carried by the head.

30 14. Tongs of the character described including, a pipe encircling head, a gripping element slidably carried by the head, a handle, means for operating the element directly by a line for operating the tongs including, a rod attached to the element slidably carried by the handle, and means for initially resisting relative rotation between the head and an object, including a spring pressed pipe gripping member carried by the head, including a slidably and pivotally mounted pipe engaging member on the element and a spring urging the member into engagement with the object.

40 15. Tongs including, a pipe encircling head, including a body having an opening adapted to receive a pipe, and a gate adapted to close the opening, a pipe gripping element carried by the head, a handle, and means for operating the element directly by an operating line attached to the handle including, a rod attached to the element slidably in the handle, and a pulley carried by the rod in an opening in the handle for passing the line.

50 16. Tongs including, a pipe encircling head, including a body having an opening adapted to receive a pipe, a gate pivoted to the body adapted to close the opening, and a latch for releasably holding the gate closed, a pipe gripping element carried by the head, a handle, and means for operating the element directly by an operating line attached to the handle including, a rod attached to the element slidably in the handle, and a pulley carried by the rod in an opening in the handle for passing the line.

60 17. Tongs including, a body having a re-

cess, a gate pivoted to the body adapted to close the recess, a gripping jaw slidable in the recess, a handle on the body, and means for operating the jaw by an operating line attached to the handle, including a rod slidably carried in the handle, and a rotatable pulley on the rod for passing the line.

70 In witness that we claim the foregoing we have hereunto subscribed our names this 14th day of March, 1930.
